US0D1090344S

(12) **United States Design Patent** (10) Patent No.: **US D1,090,344 S**
(45) Date of Patent: ** Aug. 26, 2025

(54) **DRONE**

(71) Applicant: **Flyby Robotics, Inc.**, Los Angeles, CA (US)

(72) Inventors: **Xuan-Truc Nguyen**, Los Angeles, CA (US); **Gursimran Bains**, Los Angeles, CA (US); **Aadish Joshi**, Los Angeles, CA (US); **Jason Huishen Lu**, Los Angeles, CA (US)

(73) Assignee: **FLYBY ROBOTICS, INC.**

(**) Term: **15 Years**

(21) Appl. No.: **29/894,494**

(22) Filed: **Jun. 9, 2023**

(51) LOC (15) Cl. **12-06**

(52) U.S. Cl.

USPC **D12/16.1**

(58) **Field of Classification Search**

USPC D12/16.1, 344, 326, 1-4, 174, 319-325, D12/327-343, 345; D21/301, 436, 441, D21/442, 443, 444, 446, 447, 448, 449, D21/450, 451, 452, 453

CPC B64C 29/0033; B64C 29/00; B64C 27/22; B64C 27/00

(57) **CLAIM**

The ornamental design for a drone as shown and described.

DESCRIPTION

FIG. 1 is a top, front, left-side perspective view of a drone showing our new design;

FIG. 2 is a bottom, rear, right-side perspective view of the design of FIG. 1;

FIG. 3 is a left-side view of the design of FIG. 1;

FIG. 4 is a front view of the design of FIG. 1;

FIG. 5 is a right-side view of the design of FIG. 1;

FIG. 6 is a rear view of the design of FIG. 1;

FIG. 7 is a top view of the design of FIG. 1;

FIG. 8 is a bottom view of the design of FIG. 1;

FIG. 9 is a top, front, left-side perspective view of the design shown in FIG. 1 in an open position; and,

FIG. 10 is a bottom, rear, right-side perspective view of the design shown in FIG. 1 in an open position.

1 Claim, 10 Drawing Sheets
